UNITED STATES PATENT OFFICE

FRANK LEE CAMPBELL, OF OAKLAND, CALIFORNIA

DESIGN FOR A SCALE

Application filed April 21, 1930. Serial No. 35,335. Term of patent 7 years.

To all whom it may concern:

Be it known that I, FRANK LEE CAMPBELL, a citizen of the United States, residing at Oakland, in the county of Alameda and State of California, have invented a new, original, and ornamental Design for Scale, of which the following is a specification, references being had to the accompanying drawing, forming part thereof.

Fig. 1 is a front elevation of a scale, showing my new design.

Fig. 2 is a side elevation of the scale showing my new design.

I claim:

The ornamental design for a scale as shown.

FRANK LEE CAMPBELL.
